ROTARY-ENGINE ROTORS

Gaëtan de Coye de Castelet, Billancourt, France, assignor to Regie Nationale des Usines Renault, Billancourt, France

Filed Oct. 4, 1965, Ser. No. 492,621
Claims priority, application France, Nov. 13, 1964,
994,904, Patent 1,422,344
1 Claim. (Cl. 123—8)

This invention relates to rotary-engine rotors cooled by a cooling liquid flowing through a peripheral passage, and more particularly to improvements in design aimed at ensuring more effective cooling.

It is customary to stiffen the wall forming the outer contour of the rotor by means of ribs which are parallel to the rotor bisecting plane and therefore located inside the peripheral passage, parallel with the direction of flow of the cooling liquid.

This flow is consequently of a laminar character and the heat transfer coefficient between the liquid and the hot wall is low.

Now it is well known that this coefficient is considerably augmented when the flow is made turbulent. Systematic experiments have demonstrated that:

the heat transfer coefficient is greatly improved when the longitudinal ribs are replaced by staggered spikes; and that the best coefficient is obtained when the ribs are arranged transversely in zig-zag fashion on the two walls of the passage.

These solutions cannot, however, be applied in practice, as the former fails to impart adequate rigidity to the casting while the latter is very difficult to carry into practice.

The present invention provides a solution the effectiveness of which lies intermediate the two solutions referred to and which consists in interconnecting the two walls of the peripheral passage by means of staggered columns.

This invention relates to rotary-engine rotors embodying this improvement.

The invention will now be more particularly described with reference to the accompanying nonlimitative exemplary drawing of a rotary-engine rotor of the four-lobed type, in which:

FIGURE 1 is a cross sectional-view of the rotor;

FIGURE 2 is a half-section taken through the line II—II of FIGURE 1;

FIGURE 3 is a section take through the line III—III of FIGURE 1; and

FIGURE 4 is a developed section through the bisecting plane IV—IV of the peripheral passage.

As FIGURE 1 clearly shows, the rotor consists essentially of a rim 1 and a hub 2.

2

Rim 1 has, coextensive therewith either over its entire perimeter or level only with the lobes involved in the explosions (as shown in the figure), an inner wall 3 connected to the rim by lateral walls 3¹ and 3², thereby forming a peripheral passage 4 through which the cooling liquid flows.

This liquid is conveyed, for instance, to the apex of the lobe through a hollow arm or spoke 5 and is discharged at the ends of the lobe through hollow spokes 6 and 7.

The present invention consists in replacing the customary arrangement (in accordance with which the rim 1 is stiffened by ribs parallel to the direction of flow of the liquid, i.e. in this case parallel to the bisecting plane of the rotor) by staggered columns 8.

Thus, as is more particularly shown on FIGURES 2, 3 and 4, provision may be made, for instance, for five rows of columns. At the places where they cannot be provided, for example at the outlets of the hollow spokes, the columns are replaced by spikes 9 devoid of contact with the wall 3.

Consequently, all other things being equal, cooling is improved, that is to say that the temperature rise in the rotor is smaller than with the customary arrangement in which the rim is stiffened by ribs.

I claim:

A rotary-engine rotor comprising a peripheral passage which is formed by the rotor rim and an inner wall connected thereto by lateral walls and through which flows a cooling fluid, characterized in that the inner rim surface forming the outer wall of said passage is connected to said inner wall by staggered columns, it being possible for said columns to be replaced locally by spikes at points where said inner wall is absent.
